UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

PERCUSSIVE FIRING MECHANISM.

1,105,627.

Specification of Letters Patent.

Patented Aug. 4, 1914.

Original application filed October 18, 1913, Serial No. 795,854. Divided and this application filed April 6, 1914. Serial No. 829,829.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in Percussive Firing Mechanism, of which the following is a specification.

This invention relates to percussive firing mechanism for breech loading guns, of the kind in which the striker is released by a trigger or firing handle mounted on the gun carriage.

The chief object of the present invention is to provide improved means whereby the trigger or firing handle can be mounted on a part of the carriage which is not co-axial with the gun trunnions, and the operative relationship between the said trigger or handle and the striker can be maintained notwithstanding the movements of the gun in elevation or depression.

In order that the said invention may be clearly understood and readily carried into effect, we will describe the same more fully with reference to the accompanying drawings, in which:—

Figures 1 and 2 are respectively a side elevation and a sectional plan showing a constructional form of the invention.

A is the gun, B the gun cradle, B' one of the trunnions and C the gun carriage.

D represents the aforesaid device which is pivoted at d to the cradle.

D' is the trigger or firing handle and D² the firing shaft.

E is the elevating hand wheel or lever.

In the example shown, the aforesaid device D is in the form of a curved plate the pivot d of which is arranged parallel to the trunnions and in front thereof when the gun is horizontal.

The firing trigger D' is carried on the handle of the elevating hand wheel or lever E which is mounted on the gun carriage. The said trigger operates through the known arrangement of a sliding pin d³, a

lever d^{3x} and another sliding pin d⁴ upon an arm d^{4x} on a vertical shaft d⁵ mounted on the carriage. This shaft has another arm d^{5x} carrying a roller d⁶ for engaging with the curved plate D. The curved plate D is connected by means of the firing shaft D² to an arm D⁸ which carries a bevel pinion D^{8x} meshing with a similar pinion forming part of or connected to a sleeve D^{4x}. This sleeve is mounted on the cradle and carries a plunger D⁶ which is adapted to engage with a sleeve D^{6x} carried by the gun, in a similar manner to that described in the prior British specification No. 16216 of 1911.

What we claim and desire to secure by Letters Patent of the United States is:—

1. In percussive firing mechanism for ordnance, the combination with a non-elevating part of the mounting and the gun cradle, of an elevating device on said non-elevating part, a firing trigger on said elevating device, a curved member moved by said trigger, a pivot for connecting said member to the cradle, a rotary member on the cradle, means for connecting said rotary member to the curved member and a rotary firing member on the gun with which firing member the rotary member on the cradle engages.

2. In percussive firing mechanism for ordnance, the combination with a non-elevating part of the mounting and the gun cradle, of an elevating device on said non-elevating part, a firing trigger on said elevating device, a curved member moved by said trigger, a pivot for connecting said member to the cradle, a rotary member on the cradle, a rod and gearing for connecting said rotary member to the curved member and a rotary firing member on the gun with which firing member the rotary member on the cradle engages.

In testimony whereof we affix our signatures in presence of two witnesses.

ARTHUR TREVOR DAWSON.
GEORGE THOMAS BUCKHAM.
